UNITED STATES PATENT OFFICE.

DANIEL J. SUMMERS, OF WAYNESBOROUGH, PENNSYLVANIA.

CAR-COUPING.

SPECIFICATION forming part of Letters Patent No. 333,172, dated December 29, 1885.

Application filed September 7, 1885. Serial No. 176,236. (No model.)

To all whom it may concern:

Be it known that I, DANIEL J. SUMMERS, of Waynesborough, in the county of Franklin and State of Pennsylvania, have invented certain new and useful Improvements in Car-Couplers; and I do hereby declare the following to be a full, clear, and exact description of the invention, such as will enable others skilled in the art to which it appertains to make and to use the same.

My invention relates to an improvement in car-couplings.

On the 14th of May, 1878, Letters Patent for an improvement in car-couplings was issued to J. B. Raby and myself, in which a spring-cushioned buffer served to lock and release at the proper time, a pivoted link, which latter, when released from its locked position for coupling, was adapted to drop over a horn or hook on the opposite draw-head.

The object of my present invention is to provide a car-coupling adapted to operate upon the same general principles as the one referred to above, but so modified as to render it more practicable, simpler, and better adapted to general use in connection with cars supplied with the ordinary link or other styles of couplings.

With these ends in view my invention consists in certain features of construction and combinations of parts, as will be hereinafter described, and pointed out in the claims.

In the accompanying drawings, Figure 1 is a view of the coupling in longitudinal vertical section, showing it in locked adjustment, and also showing in dotted lines the position of the hook-link in its elevated adjustment, ready for coupling; and Fig. 2 is a plan view of one section of the coupling.

A A' represent a pair of draw-heads adapted to be coupled together. They are of the same form and construction, their shanks *a* being preferably hollow, and as light as is consistent with the required strength. The meeting ends 45 of the draw-heads are provided with vertical open slots *B*, the ends of the branches of the draw-head on each side of the slot being enlarged, as shown at *b*. The inside faces of the branches are provided with channel-grooves 50 *C*, extending from the ends *b* back to a cross tie or plate, *D*, cast integral with the draw-

head. A spring-cushioned buffer, consisting of a pair of heads, *E*, having a pair of guides, *e*, formed integral therewith and adapted to fit and slide within the grooves *C*, the rear ends of the guides *e* being connected by a cross-tie, *F*, is provided with guide-studs *f*, projecting from the back faces of the heads *E*, adapted to fit in sockets *G*, formed in the ends *b*, which serve to steady the buffer in its sliding movement. The ends of the cross-tie *F*, at points in close proximity to the inner faces of the branches of the draw-head, are provided with upwardly-extending hooks *g*. A rod or bolt, *H*, is screwed into the back face of the cross-tie *F*, and has a sliding motion within a perforation, *h*, in the cross-plate *D*. A spring, *K*, is secured on the bolt *H* between the tie *F* and the plate *D*, the tension of which tends to force the buffer *E* outwardly. Its motion in that direction is limited and adjusted by the nut *d* on the inner end of the bolt *H*. A cross-pin, *I*, extends through the branches of the draw-head in the rear of the ends *b* and above the grooves *C*, being located about midway 75 between the upper and lower edges of the branches of the draw-head. Slight recesses *i* are formed on the inner faces of the branches to admit adjusting-collars *k* or the hubs of the vertically-swinging section *L* of the coupling-hook. The section *L* consists of a strong piece of metal terminating at one end in a pair of arms, *l*, adapted to embrace snugly the cross-pin *I* and not turn thereon, and at the other end in a pair of transverse jaws, *l'*, between 80 which the laterally-swinging section *M* of the coupling-hook is pivotally secured by an ordinary coupling-pin, *m*. The ends of the arms *l* terminate in upwardly-extending noses *l''*, adapted to engage the hooks *g* when the coupling-hook *L M* is in elevated adjustment, and the shape of the hook *g* and the nose *l''* is such that when the coupling-hook is elevated the nose *l''* will act as a cam in engagement with the hook *g* and will force the hook *g* backwardly until the nose *l''* comes into engagement with notch of the hook, which will then, through the tension of the spring *K*, lock the coupling-pin in elevated adjustment. 95

Suppose two cars provided with the above-described couplings to be approaching each other for the purpose of coupling, one of the 100

coupling-hooks will be dropped into the position shown in connection with the draw-head A', and the other will be elevated and automatically locked in the position shown by dotted lines in connection with the draw-head A. When the two buffers E come in contact, the hook g will be slid back out of engagement with the coupling - hook L M, and the latter will fall into the position shown in Fig. 1, hooked over the cross-pin I of the draw-head A', the cross-pin I thus forming both a pivotal support for the coupling-hook and a locking-pin for the opposite hook. The slanting faces shown on the buffers E and their longitudinal play admit of the cars assuming the angular positions with respect to each other required in passing around a curve, while the laterally and vertically swinging coupling-hooks will assume all the different positions which may be required in coupling cars of different heights, turning curves, &c. The vertically - swinging section L of the coupling-hook, when the section M is removed, is particularly convenient in coupling thereto a car provided with one of the ordinary link-and-pin couplings, since it will adjust itself to such an angle as to admit a straight link either from a car higher or lower than itself, doing away with the necessity of selecting a goose - neck link.

The cross - pin I, working loosely in the branches of the draw - head and having the section L secured thereon, is adapted to be rotated to elevate the coupling-hook by a side lever (not shown) pivotally secured in its bifurcated head n, or other approved devices may be employed, as found most convenient.

Having fully described my invention, what I claim as new, and desire to secure by Letters Patent, is—

1. In a car-coupler, the combination, with a two-branch draw-head and a cross-pin loosely secured in the branches, of a vertically and laterally swinging coupling - hook, a spring-actuated buffer, and a sliding hook connected with the buffer and located in the same plane with and behind the coupling-hook, substantially as set forth. 45

2. In a car-coupling, the combination, with a two-branch draw-head and a cross-pin loosely secured in the branches, of a coupling-hook consisting of a vertically-swinging section secured on the cross-pin between the branches of the draw - head, and a laterally - swinging section pivotally secured in the free end of the 55 aforesaid section, substantially as set forth.

3. In a car-coupling, the combination, with the two-branch draw-head and the vertically-swinging coupling-hook secured between the branches, of the spring-actuated double-headed 60 buffer adapted to slide in channels formed in the branches of the draw-head, and provided with a hook adapted to engage the shank of the coupling-hook and hold the same in a position for coupling, substantially as set forth. 65

4. In a car-coupling, the combination, with the two branch draw-head and the vertically-swinging coupling-hook, of the spring-actuated buffer adapted to lock and release the coupling - hook, and provided with guide - studs 70 adapted to work in sockets in the draw-head and steady the sliding movement of the buffer, substantially as set forth.

In testimony whereof I have signed this specification in the presence of two subscribing witnesses. 75

DANIEL J. SUMMERS.
